UNITED STATES PATENT OFFICE.

MAX L. WIENER, OF NEWARK, NEW JERSEY.

BUS-BODY SILL.

Application filed November 16, 1926. Serial No. 148,634.

This invention relates to frame structures for wheeled vehicle bodies, particularly to types used in omnibus construction and has special reference to the sills and posts as carried by the chassis.

In such structures it is desirable to maintain the flooring at as low a level as is possible, to provide adequate supports for the superstructure, these to include longitudinally extending beams or sills on each side and means for effectively and securely fastening the body posts to the sills.

It is a further feature to improve the posts by rendering them in condition to be readily bent at their lower ends and at the same time materially reenforced.

It is also an important object to provide a sill structure of simple character, possessing great strength and ability to resist flexure in any direction, and which is light in weight and essentially practical to construct.

These several advantages are accomplished by the novel construction and arrangement of parts hereinafter described and shown in the accompanying drawing, forming a material part of this disclosure, and in which:—

Figure 1 is a fragmentary longitudinal sectional view showing an embodiment of the invention, the section being taken on line 1—1 of Figure 2.

Figure 2 is a partial transverse sectional view of the same, taken on line 2—2 of Figure 1.

Figure 3 is a fragmentary perspective view of one of the sill elements in detail.

Figure 4 is a fragmentary perspective view of the sill and frame post.

In these views the numeral 10 designates one of a pair of conventional chassis side frames, the same being of channel shaped cross section with the web presented outwardly and reach the full length of the truck.

In order to provide the necessary width required for a bus body, a plurality of outriggers 11 are secured at spaced intervals to the webs of the channels 10, the outriggers being comprised of a flat metal plate bent to present a triangular brace 12 having at its base a flange 13 held by rivets 14 to the channel web; bent at a right angle from the upper, straight edge of the brace 12 is a horizontal shelf 15, extending over the base 13 and reaching over the upper flange of the channel 10 to be held by rivets 16.

These out-riggers act as supports for sills, generally designated by the numeral 17, the same consisting of rolled Z bars having webs 18 and upper and lower flanges 19 and 20 respectively.

The lower flange is provided with a series of small openings 21 to receive floor bolts and larger openings 22 to receive bolts 23 passing through the floor, flange and upper element 15 of the out-riggers near their outer ends.

The upper flange 19 is sheared to present openings 24, the material between the cuts being bent upwardly to form lugs 25 registering with the web 18 of the sill, and the web and lugs are provided with perforations 26 to receive bolts.

The posts 27 are of such width as to neatly fill the flange spaces 24, and shaped to seat against the lugs 25, being secured by bolts 28 passing through the openings 26.

The lower outer corners of the posts are levelled and have secured thereon longitudinal nailing strips 29 by which the covering 30 of the vehicle is secured at its lower edge.

These strips abut the lower portions of the sills and rest on plates 36 bolted to the sill flange 20.

Prior to bending the lower ends of the posts, a series of saw cuts are made in them and these kerfs filled with a thin strip or veneer 30 of hard wood held by a suitable cement.

It is found that the cuts enable the wood to bend far more easily than solid ends in assuming the desired shape and the veneer acts to reenforce the same as if they were solid.

The flooring 31 preferably consists of sheets of laminated material disposed transversely in the body to rest at their ends on the sill flanges 20 to extend from side to side and are held by bolts 32 passing through the opening 21 in the flanges.

Directly over the flanges of the frame 10 are strips of rubber 33 or similar material adapted to prevent squeaking, due to direct frictional contact of the floor with the flanges, and above the sheets 31 is the usual covering 34 of cement or the like applied in a plastic condition, or linoleum as may be preferred.

Although the foregoing is descriptive of the preferred embodiment of the invention, it will be apparent that minor changes may be made in its construction, without the ex-

ercise of invention or conflicting with the scope of the claims hereto appended.

Having thus described my invention, what I claim as new and desire to secure by Letters Patent, is:—

1. A bus body support comprising in combination with the side frame bars of a vehicle truck, of out-riggers riveted to said bars to extend oppositely outward, Z bars having their lower flanges bolted to said out-riggers and their upper flanges spacedly notched, posts guided by being entered within the notches, the portions of said flanges displaced to form the notches being raised and used; to secure said posts to said Z bars, and a floor resting on the lower flanges of said Z bars.
2. A bus body support comprising in combination with the side frames of an automobile chassis, of out-riggers riveted to said side frames to extend oppositely outward, Z bars having their lower flanges bolted to said out-riggers and their upper flanges sheared to produce openings having up-standing lugs, plates bolted on said lower flanges, posts having their lower ends fixed

in the mentioned openings to rest on said plates, said posts being bolted to said lugs and Z bar webs, a floor having its lateral edges bolted on the lower flanges of said bars, and cushion elements disposed between said floor and the upper elements of said chassis frames.

3. In a bus body, the combination with a vehicle truck, of Z shaped sill members carried by the truck, the upper outstanding flanges of said sills being sheared to produce notches extending to their upright webs, plates secured to the lower flanges of said sill to register with the notches, and posts resting on said plates to engage the notches.

4. In a bus body frame, a bent wooden post having a plurality of spaced kerfs in its lower end prior to bending, the kerfs extending transverse to the direction of bending and to a depth equal to the length of bend, and a hard wood filler cemented in the kerfs to completely fill the space therein.

Signed at New York in the county of New York and State of New York this 13 day of November A. D. 1926.

MAX L. WIENER.
